SLOT ANTENNA WITH HORN

Victor H. Rumsey, Urbana, Ill., and Carlton H. Walter, Columbus, Ohio, assignors to the United States of America as represented by the Secretary of the Air Force

Filed Mar. 10, 1955, Ser. No. 493,580

3 Claims. (Cl. 343—767)

This invention relates to a slorn antenna and particularly to a traveling wave slot with a horn aperture constituting a shaped beam antenna especially suited to operation in the microwave region.

In the application of antennas to vehicles, particularly high speed vehicles, such as aircraft, it is desirable to provide an antenna which creates a minimum disturbance of the outer surface of the vehicle. Also, it is usually desirable that the antenna be highly directional and have low side lobe losses.

It has heretofore been proposed to provide a slot antenna which consists essentially of a traveling wave slot in the side of a rectangular waveguide. These slot antennas have been undesirable because of the wide conical beam and high side lobes.

The present invention improves the characteristics of the slot antenna by providing a horn operative to match the slot to free space, the diverging angle of the horn being effective to reduce the width of the conical beam to improve the focusing action and to materially improve the poor radiation characteristic of the normal slot. It has been found that the geometry of the horn may be modified along its length to control the radiation amplitude along the slot with very little change in phase velocity.

It is accordingly an object of the invention to provide an improved antenna.

It is a further object to provide a slorn antenna.

It is another object of the invention to provide an antenna giving a highly directional beam.

Other objects and advantages of the invention will be apparent from the following specification taken in conjunction with the accompanying drawings in which:

FIGURE 1 is a perspective view of a slot antenna mounted flush in a ground plane;

FIGURE 2 is a view similar to FIGURE 1 and showing a tapered slot antenna;

FIGURE 3 is a perspective view of a slorn antenna;

FIGURE 4 is a perspective view of a tapered slorn antenna;

FIGURE 5 is an elevational view of a tapered slorn mounted in a ground plate;

FIGURE 6 is a top plan view of the mounted slorn antenna;

FIGURE 7 is a graphic presentation of the conical pattern of the slorn antenna; and

FIGURE 8 is a similar presentation of the E-plane characteristic.

In the construction according to FIGURE 1, a slot type antenna is constructed by providing a waveguide 10 with an elongated slot 12 in one of the faces, preferably a narrow face. The slot 12 is usually mounted flush with a ground plate 22 such as the outer skin of a vehicle. If such an antenna is oriented for maximum signal and then rotated about its axis, the resulting pattern 26 (see FIG. 7), known as a conical pattern, illustrates the width of this beam. The half-power points are found to subtend an angle of approximately 150°. It was found that the typical wide conical angle of this type antenna could be improved by changing from the usual transverse electric feed to a transverse magnetic feed, as shown, by coupling the coaxial feed cable 14 into the end of the waveguide

2

10 with the inner conductor 16 extending substantially axially within the waveguide 10.

In the modification, according to FIGURE 2, a rectangular waveguide 18 is provided with a tapered slot 20 opening into a ground plate 22 with the waveguide 18 being provided with a transverse electric feed by having a coaxial cable 24 with the central conductor 26 extending transversely of the narrow width of the waveguide 18 adjacent to one end of the slot 20. In order to maintain a constant amplitude distribution along the length of the slot 20, the slot is reduced adjacent the feed and flared outwardly away from the feed point so that the amplitude of energy leaving the slot is substantially constant from end to end of the slot. This follows the well-known fact that as energy leaves the slot 20 less energy remains to radiate from the remainder of the slot. Therefore, the tapering of the slot 20 compensates for the reduced energy in the waveguide so that the radiation is substantially constant throughout the length of the slot.

It has been found that providing the slot with the transverse magnetic feed and with the tapered slot materially increases the focusing ability and consequently improves the operation of the antenna.

25 The beam width in the vertical pattern in the plane through the long axis of the slot and parallel to the ground plane is determined primarily by the length of the slot 20 and may be found from various known formula. In practice, it has been found that slots 20 having a length of 30 the order of 10 to 15 wavelengths have been quite effective.

25 In the construction, according to FIGURE 3, diverging horn members 30 and 32 are provided to match the narrow slot 34 to free space and operative to greatly improve the normally poor radiation characteristic of the slot. The resulting slorn antenna has a good focusing action to produce a narrow conical pattern and further permits the antenna to be oriented for desired direction and also be mounted flush with a surface 22 as shown in FIGURES 5 and 6. It has been found that horn members 30 and 32 having a radial length R of approximately five wavelengths provide good focusing action without being undesirably cumbersome. A slorn having 45 a length l of 10 to 15 wavelengths, a radial distance R of five wavelengths and a flare angle ψ of 60° produces a conical pattern with a beam width of approximately 30° at the half-power points, as shown at 54 of FIG. 7.

50 The geometry of the slorn lends itself very well to the suppression of the side lobes 56 of FIG. 8. The amount of radiation along the slot is controlled by varying the geometry of the horn along the length of the antenna. An amplitude distribution that gives negligible side lobes can be obtained by providing a taper 36 and 38 on the 55 horn members 30 and 32. Experiments indicate that the taper is not particularly critical. Tests show a remarkable suppression of the side lobes with very little change in the beam width of the conical pattern.

55 It is difficult to formulate the exact relation between 60 amplitude distribution and horn taper. However, qualitative considerations have led to good results. By considering the antenna as a continuous array of sectional horn elements the length and flare angle ψ of each sectional element can be selected to control the energy flow into the slot 34 in a prescribed manner. Usually it will be found that the flare angle ψ can be kept constant and only the length l of the slot 34 varied. The angle of maximum radiation is determined by the phase velocity along the slot. This is controlled by the geometry of the slot, the dielectric with which it is filled, and the type of excitation. The beam width in the vertical pattern is determined

by the length of the slot. In this case the slot 34 is approximately 13 wavelengths along and produces a half power beam width of about 10 degrees. The 60 degree flare angle ψ and the average horn length R of approximately five wavelengths produces the 30 degrees transverse beam. Remarkably low side lobes are obtained by the taper which results in amplitude distribution that is approximately sinusoidal. The straight line taper of FIGURE 4 was used because of its simplicity. It was found that X could be carried from 0 to $L/2$ with good side lobe reduction. In the interest of minimum transverse beam width X should be as long as is practical for a given side lobe level.

When it is desired to mount the slorn antenna flush with a surface other considerations are involved. A sketch of the flush mounted slorn is shown in FIGURES 5 and 6. End plates 40 and 42 are provided at each end of the horn members 30 and 32. It has been found that the end plates 40 and 42 must be substantially parallel to the axis of maximum radiation in order to suppress reflections at the plates. The effective radial length R then becomes the average of the length R_1 and R_2 of the end plates 40 and 42. The length l of the slot 47 in the waveguide 44 determines the radiation angle θ_m . The waveguide 44 is mounted at the angle to the ground plate 22 to determine the beam direction angle δ . The length l of the slot 46 in the waveguide 44 is related to the length L of the aperture 48 in the ground plate as indicated by the formula

$$l = \frac{L \sin \delta}{\sin \theta_m}$$

In order to prevent a reverse feed lobe, it is desirable to absorb or dissipate the energy reaching the end of the waveguide 44 and a dissipative load 50 is placed in the end of the waveguide 44.

The transverse beam width is still determined by the excitation; the flare angle ψ , and R_{av} where R_{av} is the average length of the end plates 40 and 42. The beam width in the vertical pattern is determined by the length L of the aperture 48 in the ground plane 42. Broadside radiation is obtained by slanting the feed end of the antenna in FIG. 5 away from the ground plane to permit θ to be 90°, since in practice θ_m is limited to about 80°.

In a practical construction of the slorn type antenna it is customary to utilize a flush mounting with an angular disposition of the rectangular waveguide 44 and to utilize transverse magnetic feed so that a narrow conical pattern will be secured as indicated at 54 in FIGURE 7 and the end plates together with the tapered horn construction reduce the substantially minimum side lobe patterns 56 as shown in the E-plane characteristics of FIGURE 8.

In the operation of the slorn type antenna the length l

will be selected to secure the desired vertical pattern and the horn angle ψ will be selected to provide the radiation pattern and to suppress the side lobes of the E-plane pattern. In general, the traveling wave slot 46 will be mounted at an angle to the ground plane 22 so that radiation may be directed substantially longitudinally of the supporting vehicle.

For purpose of exemplification, particular embodiments of the invention have been shown and described according to the best present understanding thereof. However, it will be apparent to those skilled in the art that various changes and modifications in the construction and arrangement of the parts thereof may be readily resorted to without departing from the true spirit of the invention.

15 We claim:

1. A directional antenna comprising a rectangular waveguide, one side of said waveguide being open to provide an elongated slot, means operatively connected to provide excitation in said waveguide, an outward flaring horn mounted on said waveguide and communicating with said slot throughout its length, said horn having a radial length of the order of five wavelengths and a flare angle of the order of 60 degrees.

2. A directional antenna comprising a rectangular waveguide, one side of said waveguide being open to provide an elongated slot, means operatively connected to provide excitation in said waveguide, an outwardly flaring horn mounted on said waveguide and communicating with said slot, said horn being tapered, end plates on said 20 tapered horn, said end plates being essentially parallel to rays of maximum radiation from the slotted waveguide, a ground plane having an opening adapted to receive said horn; said horn open flush with the outer surface of the ground plane.

3. A directional antenna system comprising a ground plane, a rectangular waveguide mounted in angularly spaced relation to said ground plane, the side of said waveguide presented to said ground plane being open to provide an elongated slot, means operatively connected to provide excitation in said waveguide, an outwardly flaring horn mounted on said waveguide and communicating with said slot throughout the length thereof, end plates on said horn, said end plate being substantially parallel to rays of maximum radiation from the slot in said waveguide, said ground plane having an opening adapted to receive said horn, said horn terminating flush with the outer surface of said ground plane whereby said horn is tapered longitudinally.
